UNITED STATES PATENT OFFICE.

WILLIAM E. SHORE, OF NEW YORK, N. Y., ASSIGNOR TO COMBUSTO DEVICES
CORPORATION, OF NEW YORK, N. Y., A CORPORATION OF NEW YORK.

AIR-SUPERHEATING DEVICE FOR FURNACES.

1,157,964.

Specification of Letters Patent. Patented Oct. 26, 1915.

Application filed June 17, 1914. Serial No. 845,624.

To all whom it may concern:

Be it known that I, WILLIAM E. SHORE, a subject of the King of Great Britain, residing at New York, in the County of New York and State of New York, have invented certain new and useful Improvements in Air-Superheating Devices for Furnaces, of which the following is a specification.

This invention relates to improvements in air superheating devices for use in superheating air in furnaces, and the like, to aid combustion.

While it is intended to superheat the air passing through the superheater by radiation of the heat from the metallic casing, the heat being supplied by the fuel in the furnace, the principal object of the invention is to combine with the superheater, an auxiliary heating means for use temporarily, that is to say, to heat the air in the heater when the fire is being started, in order to facilitate and quicken the fire in the furnace, which, thereafter, heats the superheater to a high degree of heat, causing it to highly superheat the air as it passes therethrough.

A further object of the invention is to so construct the superheater that the air will be passed back and forth therein over very considerable area or surfaces of hot metal, so as to heat the air to an exceedingly high temperature, before it is introduced into and mixed with the gases or products of combustion in the furnace.

In the drawings, Figure 1 is a top plan view of the heater, showing in section, a fragment of the furnace wall and fire-door, to which the superheater is attached, showing the manner of supplying gas to the heater for preliminary heating. Fig. 2 is a front elevation of the same, part of the fire-door being broken away, to show the air inlets of the heater, and the damper for controlling them; Fig. 3 is a vertical section taken about on line *a—a* of Fig. 2; Fig. 4 is another vertical section taken about on line *b—b* of Fig. 2. Fig. 5 is a front view of the heater with the door and front plate partly broken away, there being shown in one of the compartments of the heater, an electric heating coil instead of the gas appliance, according to Figs. 1 and 2; Fig. 6 is a central sectional view about on line *c—c* of Fig. 5, the distributor being omitted.

Referring to the drawings, the numeral 1 designates the superheater casing, substan-

tially rectangular in form, and provided with front and rear walls 2 and 3; top and bottom walls 4 and 5 and end walls 6 and 7.

The front wall 2 is removable and fits in snugly between the front flanges 8 of the casing, wherein it may be secured by any suitable means. This wall 2 stops short of the bottom 5 of the casing, thus providing between the bottom of the wall and the bottom of the casing air inlets 9 leading from a preheating chamber 10 formed between the front wall 2 and the furnace fire-door 11. The door is provided with suitable vents 12 through which air enters the chamber 10 preparatory to being conducted through the heater, to which fire-door the heater is rigidly secured by means of bolts 13 passing through the fire-door, and into lugs 14 provided integral with the side walls of the casing, as better shown in Fig. 5.

The numerals 15, 16, 17 and 18 designate a series of transverse partitions which, together with the bottom 5 of the casing, and the vertical partitions 19, form a series of conduits or passages 20 which are in communication with each other through passages 21, 22, and 23, the passages being formed alternately between the rear and front edges of the partitions 15, 16, 17 and 18, and the uppermost conduit communicates with an outlet conduit 24 formed between the partitions 18, and the lower partition 25 of the upper series of partitions, through a passage 26 formed between the rear side of the wall 2 and the front end of the partition 18. The passage 24 opens through the rear wall 3, as indicated at 27, in horizontal line with a series of such openings extending entirely across the outlet end of the casing, as indicated in dotted lines, Figs. 1 and 3.

The numeral 28 designates another series of inlet openings through the wall 2 of the heater. The lower series of openings communicates with conduits or passages 29 formed between the partition 25 and the transverse partition 30, like the lower partitions, extending from side to side of the heater. Above the partition 30 are other transverse partitions 31, 32, and 33, which, together with the top floor of the casing, form a series of conduits 34, 35, 36 and 37, which are in communication alternately, at the rear and front of the casing, through passages 38, 39, 40 and 41, the uppermost

passage leading to the outlet opening 42, at the rear top of the casing, thus forming a series of outlet openings corresponding to the lower outlet openings 27.

5 The numeral 43 designates what I call the distributor end of the casing, which comprises a casting having closed sides and top, the top being curved so as to slightly overlap the top floor of the casing, to which the 10 distributor is rigidly attached, by means of bolts 44, or other suitable means. The front of the distributor is provided with a series of apertures or outlet openings 45, which communicate with spaces 46 between a series of vertical ribs 47 and 48, the ribs 47 being generally narrower than the ribs 48, so as to leave a space 49 between said ribs and the rear face of the casing, against which the distributor fits. The ribs 48, which preferably alternate with the ribs 46, are cut away, as indicated at 49' and 50, the cut away portions 49' coming opposite the outlet openings 42, and the cut away portions 50 coming opposite the outlet openings 27, thus 15 providing for lateral circulation through the distributor, between the ribs. The bottom of the distributor is provided with a series of downwardly opening outlet openings 51, communicating with the spaces between the various ribs, so that when the superheated air, after having been passed alternately back and forth, through the casing between the various partitions and through the various conduits, will be discharged through the openings 27 and 42 into the distributor, where it will come in contact with the hot surfaces of the distributor, and be further superheated and ultimately discharged through the outlet openings 45 and 51, where 20 it mixes with the products of combustion in the furnace. The superheated air, passing through the underneath openings 51 of the distributor, forms a cloak or envelop around the lower edge of the distributor, thus insulating it, to some extent, from the very intense heat of the furnace, which prevents the metal of the distributor from burning away at its lower edge.

As the air enters the inlets 9 and 28, after 25 having been heated to a considerable extent in the preheating chamber 10 formed between the inner face of the fire-door and the front wall of the heater, it comes in contact in passing through the casing, with the highly heated surfaces forming the vertical and horizontal partitions, and by so doing, becomes further heated and expanding, passes through the various conduits or passages, until it is discharged in a highly 30 heated state, into the distributor, where it is further superheated and ultimately discharged into the furnace. The heater casing extends well out into the furnace over the fire, in a position wherein it is intensely heated, heated to such a degree, in fact, that

by the time the air has passed through the deviating passages, back and forth from the front to the rear of the casing, it has attained a degree of heat approximating 900 to 1000 degrees F., or approximately the 70 "flashing" point of common gases, so that obviously, it will quickly mingle with the products of combustion, and consume the free carbon in such products, and convert them into a combustible gas, which is readily consumed, thus eliminating smoke, and aiding in combustion.

The numeral 52 designates two gas nozzles, which are provided on their under side with lighting apertures 53. These nozzles 80 are supported in bosses 54 in the front wall 2, and extend for some distance into the casing. Their outer ends are connected by a branch pipe 55 which receives centrally, a vertical pipe 56, the upper end of which is connected by an angle connection 57, with a pipe 58, whose outer end is received in the sleeve 59 of a swivel valve 60, communicating with the main gas pipe or connection 61. This swivel valve is centered with the hinges 90 62 of the fire-door 11, so that the door may be opened and closed without interfering in any way, with the gas connection. These burners are arranged in horizontal line with each other, and in two of the conduits in 95 the lower series of transverse and vertical partitions, and serve to heat the air passing through their immediate conduits, and the adjacent conduits on either side of the burner. These burners are lighted when the 100 fire is being started and when it is desired to facilitate combustion and quicken the fire, and after the fire has become sufficiently hot, so that it can be depended upon to bring the heater casing to a very high degree of 105 heat, the gas supply may be cut off.

In the form of heater shown in Figs. 5 and 6, the auxiliary heater is placed in a compartment immediately above the inlet openings 28, the horizontal partition 31 being in this form, omitted, as well as the vertical partitions between the partitions 30 and 32. The numeral 63 designates an electric heating coil which may be of any approved construction, and it is supported 110 upon a series of rods 63' mounted preferably in mica-insulation blocks 64 and 65, located respectively in the front and rear walls 2 and 3, there being a suitable electrical connection 66 for supplying current to the 120 heating coil.

The numeral 67 designates a damper which normally covers all of the conduits, except the inlet openings 9 and 28, and is provided, in its upper portion, with a series of horizontally arranged openings 68, adapted to control the inlet openings 28, upon the vertical movement of the damper. The lower end of the damper normally ends at the top of the inlet openings 9 and the ver- 125 130

tical movement of the damper is such that it will simultaneously control the air supply to both the openings 9 and 28. The vertical movement of the damper is brought about by a cam 69 which is carried upon a short shaft 70 suitably journaled in the wall 2 and extending through the fire-door 11, outside of which it is provided with a hand wheel 71. The cam 69 works in a cam slot 72 in the damper, so that obviously, when the hand-wheel is turned, the cam will lift or lower the damper and thereby enlarge or diminish the inlet openings 9 and 28, as the exigencies of the case may require.

15 The top of the casing is provided with openings 73 for the passage of the gas from the burners 52.

It will be noted that the chambers or spaces formed by the various horizontal partitions, increase in cross sectional area, thus giving the air, which has been, to some extent, preheated, space in which to expand as it passes from chamber to chamber, becoming in the meantime, more expanded. 25 This additional room for expansion, as the air becomes hotter, permits the air to pass through the superheater with even velocity thus preventing any retarding of the air, by reason of its increased volume. However, it 30 will be seen that the provision of the various conduits formed by the vertical partitions extending to a greater or less extent into the casing, resists or retards the too free movement of the air through the casing, by 35 reason of the skin friction of the air against the metal, which, it will be understood, is very highly heated from the heat of the furnace, so that, as the air comes into the inlet opening and is passed to and fro through 40 the casing contacting with various metal surfaces, it becomes extremely hot, so that by the time it is discharged through the outlet openings 27 and 42, it is extremely hot and after contacting with the hot surfaces 45 of the distributor 43, it is further superheated, and discharged into, and intermingles with the gases or products of combustion from the fuel, thus producing additional heat in the furnace, by reason of con- 50 suming the free carbon or unconsumed fuel in the furnace. The advantageous results of this are obvious, as there is practically no smoke, an indication that the fuel usually wasted, is consumed.

55 Having thus described my invention, what I claim is:—

1. A superheater comprising a casing adapted for attachment to a furnace and to extend into the fire-pot thereof, provided 60 with a plurality of intercommunicating chambers, there being an inlet opening communicating with said chambers, and an outlet opening leading from said chambers, through which the superheated air is dis- 65 charged into the combustion chamber, and

an auxiliary heating means for supplying heat to the superheater, independent of the heat supplied by the products of combustion in the furnace, for the purposes set forth.

2. A superheater adapted for attachment to a furnace and to extend into the fire-pot thereof, provided with a plurality of intercommunicating chambers, there being an inlet opening communicating with said chambers, and an outlet opening leading from said chambers, through which the superheated air is discharged into the combustion chamber, and a gas burner in said casing, and adapted to supply heat to heat 80 the air in said chambers, as and for the purposes set forth.

3. In combination with the fire door of a furnace, a superheater comprising a casing having horizontal partitions therein with 85 passages therethrough dividing it into intercommunicating chambers, there being suitable inlet and outlet openings, an auxiliary heater extending into said casing, to supply heat independently of the heat from the 90 products of combustion of the furnace.

4. The combination with the fire door of a furnace, a superheater comprising a casing secured to said door, and provided with a plurality of horizontal partitions provided 95 with openings, whereby the spaces between said partitions are placed in intercommunication, and a series of vertical partitions between the horizontal partitions, forming conduits for the passage of the air which is heated by radiation from said horizontal and vertical partitions, there being suitable inlet and outlet openings through which the air to be superheated is admitted to the casing and discharged therefrom respec- 100 tively, and an auxiliary heater adapted to supply heat independent of the heat from the products of combustion of the furnace.

5. In combination with the fire door of a furnace, a superheater comprising a casing 110 adapted to be secured to said door, and provided with a plurality of intercommunicating chambers, there being an air inlet for admitting the air to said chambers, and an outlet opening for discharging the air there- 115 through, and a distributor casing secured to the rear end of the superheater casing, said distributor casing being provided with apertures for the discharge of the superheated air which has passed through the main body 120 of the casing, in which distributor casing the air becomes further superheated before being discharged, and intermingles with the products of combustion of the furnace, and an auxiliary heater within the casing adapt- 125 ed to supply heat independent of that supplied by the fuel in the furnace.

6. In combination with the fire door of a furnace, a superheater comprising a casing adapted to be attached to said door, said 130

casing being provided with a plurality of intercommunicating chambers, there being an inlet and outlet opening communicating with said chambers, a gas burner extending into the casing and adapted to supply heat independent of the heat supplied by the products of combustion in the furnace, said burner being supplied with gas by a connection mounted concentric with the hinge

of the furnace door, so that the opening and closing of the door will not interrupt or break said connection.

In testimony whereof I affix my signature in presence of two witnesses.

WILLIAM E. SHORE.
